LIGHT RESPONSIVE APPARATUS

Paul H. Crago, Wilkinsburg, Pa., assignor to The Union Switch & Signal Company, Swissvale, Pa., a corporation of Pennsylvania

Application October 27, 1934, Serial No. 750,345

10 Claims. (Cl. 246—29)

My invention relates to light responsive apparatus, and has for an object the provision of novel and improved means for controlling an electrical device in response to the action of 5 light.

I will describe three forms of apparatus embodying my invention, and will then point out the novel features thereof in claims.

In the accompanying drawing, Fig. 1 is a diagrammatic view showing one form of apparatus embodying my invention. Fig. 2 is a view showing one form of vehicle detecting system also embodying my invention. Fig. 3 is a view showing another form of vehicle detecting system 15 embodying my invention.

Similar reference characters refer to similar parts in each of the several views.

Referring first to Fig. 1, the reference character A designates a device having a magnetizable core 2 provided with two windings W¹ and W², so that these windings are in mutual inductive relation. The first winding W¹ is provided with a circuit including a source of alternating current the terminals of which are designated 20 X and Y, and the primary P of a transformer T. The secondary S of transformer T is connected with the input terminals of a full wave rectifier R, and the output terminals of this rectifier are connected with a direct current relay B.

30 The winding W² of the device A is provided with a shunt which includes light responsive means characterized by relatively high resistance when dark, and relatively low resistance when subjected to the action of light. As here shown, this means comprises two light sensitive cells C¹ and C², each having a relatively high resistance in both directions when dark, and each having a relatively low resistance in at least one direction when subjected to the action of light. 35 These cells C¹ and C² are connected in multiple in the shunt around winding W² and are oppositely poled, so that when the cells are subjected to the action of light, the resistance of the shunt is materially reduced.

40 The reference character L designates a source of light, such as an electric lamp, the rays from which may be concentrated on the cells C¹ and C² by suitable optical means, such as a lens D.

The parts of the apparatus are so proportioned 50 that when the lamp L is extinguished, so that the cells C¹ and C² are dark, with the result that the resistance of the shunt around winding W² is relatively high, the impedance of winding W¹ is such that the current in transformer T is not 55 sufficient to effectively energize relay B; whereas

when the lamp L is lighted, so that the resistance of the shunt around winding W² is relatively low, the impedance of winding W¹ is reduced to such an extent that enough current will flow in transformer T to effectively energize 5 relay B.

It should be pointed out that while in Fig. 1, the shunt for winding W² is shown as comprising two oppositely poled light sensitive cells connected in multiple, satisfactory operation of the 10 apparatus can be obtained with a single cell by properly proportioning the parts.

Referring now to Fig. 2, the reference character H designates a stretch of railway track which is equipped with vehicle detecting apparatus embodying my invention. This apparatus is the same as the apparatus shown in Fig. 1, except that the two light responsive cells C¹ and C² are located at spaced intervals along the track and are provided with individual light sources L¹ and 20 L², respectively. Each cell and its associated source of light are located on opposite sides of the track and are so arranged that the cell normally receives light from its associated source but that the rays are intercepted by a vehicle 25 moving along the track. In this case the parts are so proportioned that relay B will become de-energized when the rays of light to either cell are interrupted, and will subsequently remain de-energized until both cells are again illuminated. 30

The operation of the apparatus shown in Fig. 2 is as follows: Normally both cells C¹ and C² are lighted so that relay B is energized. When a car or train passes either cell, it will intercept the light rays normally striking such cell, whereupon relay B will release. When relay B once releases, it will subsequently remain released until both cells are again illuminated. 35

Referring now to Fig. 3, the apparatus here shown is similar to that shown in Fig. 2 with 40 the exception that the polarity of the cell C¹ has been reversed, so that both cells C¹ and C² now have the same polarity relative to winding W²; and the parts are so proportioned that relay B will pick up when either cell is illuminated, but 45 will release when and only when both cells are dark.

With the apparatus arranged in this manner when a car or train traverses stretch H, relay B will become released if and only if both beams 50 become simultaneously intercepted by the car or train, and when the relay once becomes released it will remain released only so long as both beams remain dark. It will be seen, therefore, that the result of this arrangement is to provide an 55

indicating section which is equal to the length of the car or train less the distance between the light beams.

It will be seen from the foregoing that I have provided means for controlling a direct current relay by means of light sensitive cells without supplying the power for the relay directly from the light sensitive cells.

Although I have herein shown and described only three forms of apparatus embodying my invention, it is understood that various changes and modifications may be made therein within the scope of the appended claims without departing from the spirit and scope of my invention.

Having thus described my invention, what I claim is:

1. In combination, a first and a second winding in mutual inductive relation, a circuit for said first winding including a source of alternating current, a relay receiving energy from said circuit, a closed circuit for said second winding including light responsive means characterized by relatively high resistance when dark and relatively low resistance when subjected to the action of light, and means for at times subjecting said light responsive means to the action of light, said parts being so proportioned that when said light responsive means is dark the impedance of said first winding is such that said relay is not effectively energized whereas when said light responsive means is subjected to the action of light the reduced resistance of said closed circuit reduces the impedance of said first winding to such value that said relay becomes effectively energized.

2. In combination, a first and a second winding in mutual inductive relation, a circuit for said first winding including a source of alternating current, a relay receiving energy from said circuit, a closed circuit for said second winding including two light responsive devices connected in multiple each having relatively high resistance in both directions when dark and each having relatively low resistance in at least one direction when subjected to the action of light, said devices being oppositely poled in said closed circuit so that when they are subjected to the action of light the resistance of said shunt is materially reduced, and means for at times subjecting said devices to the action of light, said parts being so proportioned that when said devices are dark the impedance of said first winding is such that said relay is not effectively energized whereas when the resistance of said closed circuit is reduced by the action of light on said devices the impedance of said first winding is reduced to such value that said relay becomes effectively energized.

3. In combination, a first and a second winding in mutual inductive relation, a circuit for said first winding including a source of alternating current and the primary of a transformer, a relay connected with the secondary of said transformer, a closed circuit for said second winding including light responsive means characterized by relatively high resistance when dark and relatively low resistance when subjected to the action of light, and means for at times subjecting said light responsive means to the action of light, said parts being so proportioned that when said light responsive means is dark the impedance of said first winding is such that said relay is not effectively energized whereas when said light responsive means is subjected to the action of light the reduced resistance of said

closed circuit reduces the impedance of said first winding to such value that said relay becomes effectively energized.

4. In combination, a first and a second winding in mutual inductive relation, a circuit for said first winding including a source of alternating current and the primary of a transformer, a relay connected with the secondary of said transformer, a closed circuit for said second winding including two devices connected in multiple each having relatively high resistance in both directions when dark and each having relatively low resistance in at least one direction when subjected to the action of light, said devices being oppositely poled in said closed circuit so that when they are subjected to the action of light the resistance of said closed circuit is materially reduced, and means for at times subjecting said devices to the action of light, said parts being so proportioned that when said devices are dark the impedance of said first winding is such that said relay is not effectively energized whereas when the resistance of said closed circuit is reduced by the action of light on said devices the impedance of said first winding is reduced to such value that said relay becomes effectively energized.

5. In combination, a first and a second winding in mutual inductive relation, a circuit for said first winding including a source of alternating current and the primary of a transformer, a relay connected with the secondary of said transformer, a full wave rectifier interposed between said secondary and said relay, a closed circuit for said second winding including light responsive means characterized by relatively high resistance when dark and relatively low resistance when subjected to the action of light, and means for at times subjecting said light responsive means to the action of light, said parts being so proportioned that when said light responsive means is dark the impedance of said first winding is such that said relay is not effectively energized whereas when said light responsive means is subjected to the action of light the reduced resistance of said closed circuit reduces the impedance of said first winding to such value that said relay becomes effectively energized.

6. In combination, a first and a second winding in mutual inductive relation, a circuit for said first winding including a source of alternating current and the primary of a transformer, a relay connected with the secondary of said transformer, a full wave rectifier interposed between said secondary and said relay, a closed circuit for said second winding including two devices connected in multiple each having relatively high resistance in both directions when dark and each having relatively low resistance in at least one direction when subjected to the action of light, said devices being oppositely poled in said closed circuit so that when they are subjected to the action of light the resistance of said shunt is materially reduced, and means for at times subjecting said devices to the action of light, said parts being so proportioned that when said devices are dark the impedance of said first winding is such that said relay is not effectively energized whereas when the resistance of said closed circuit is reduced by the action of light on said devices the impedance of said first winding is reduced to such value that said relay becomes effectively energized.

7. In combination, a first and a second wind-

ing in mutual inductive relation, a circuit for said first winding including a source of alternating current, a relay receiving energy from said circuit, two closed circuits for said second winding each including a light responsive device characterized by relatively high resistance when dark and relatively low resistance when subjected to the action of light, and means for at times subjecting each of said devices to the action of light, 5 said parts being so proportioned that when either of said devices is dark the impedance of said first winding is such that said relay is not effectively energized, whereas when both of said devices are subjected to the action of light the 10 reduced resistance of said closed circuits reduces the impedance of said first winding to such value that said relay becomes effectively energized.

8. In combination, a stretch of railway track, a first and a second winding in mutual inductive 15 relation, a circuit for said first winding including a source of alternating current, a relay receiving energy from said circuit, two light responsive devices located at spaced points along said stretch of track and characterized by relatively 20 high resistance when dark and relatively low resistance when subjected to the action of light, a source of light associated with each said device and arranged to be intercepted by a vehicle moving along said track, and two closed circuits 25 for said second winding each including a different one of said light responsive devices, said parts being so proportioned that when either of said devices is dark the impedance of said first winding is such that said relay is not effectively energized, whereas when both of said devices are 30 subjected to the action of light the reduced resistance of said closed circuits reduces the impedance of said first winding to such value that said relay becomes effectively energized.

9. In combination, a first and a second winding in mutual inductive relation, a circuit for said first winding including a source of alternating current, a relay receiving energy from said circuit, a closed circuit for said second winding including two light responsive cells connected in multiple and each having relatively high resistance in both directions when dark and each having relatively low resistance in at least one direction when subjected to the action of light, 5 said cells being similarly poled with relation to said winding, and means for at times subjecting said devices to the action of light, the parts being so proportioned that the impedance of said first winding will be such that said relay will not be 10 effectively energized except when both said cells are subjected to the action of light.

10. In combination, a stretch of railway track, a first and a second winding in mutual inductive 15 relation, a circuit for said first winding including a source of alternating current, a relay receiving energy from said circuit, two light responsive devices located at spaced points along said stretch of track and characterized by relatively high 20 resistance when dark and relatively low resistance when subjected to the action of light, a source of light associated with each said device and arranged to be intercepted by a vehicle moving along said track, and two closed circuits for said 25 second winding each including a different one of said light responsive devices, the parts being so proportioned that when either of said devices is illuminated the impedance of said first winding will be such that said relay will be effectively 30 energized, whereas when both of said devices are dark the impedance of said first winding will then be such that said relay will not be effectively 35 energized.
